(57) **CLAIM**

I claim, the ornamental design for an cover for notebook, as shown and described.

DESCRIPTION

FIG. 1 is a perspective view of a cover for notebook, showing my new design;

FIG. 2 is a front elevation view thereof;

FIG. 3 is a rear elevation view thereof;

FIG. 4 is a side elevation view thereof;

FIG. 5 is a side elevation view thereof taken opposite from that of FIG. 4;

FIG. 6 is a top view thereof; and,

FIG. 7 is a bottom view thereof.

The broken lines immediately adjacent to the shaded areas depict the bounds of the claimed design, while all other broken lines are directed to environment. The broken lines form no part of the claimed design.

The “Hamelin” lettering and icon forming a part of the disclosure is a registered trademark of Holdham of Hérouville-Saint-Clair, France.

The stipple shading as used in this application is a drafting convention used to show contrast with adjacent surfaces.
